UNITED STATES PATENT OFFICE.

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed September 10, 1927. Serial No. 218,640.

My invention relates to heddle frames for looms, and it relates more particularly to improved means, in a heddle frame of the usual type, for supporting the heddle bars intermediate their ends.

The principal object of my present invention is to provide improved means, in a heddle frame, for supporting the heddle bars intermediate their ends, which will securely support said bars against undesirable motion and displacement, but which, however, will permit the bars to be quickly and conveniently mounted in and dismounted from the frame when desired.

15 In U. S. Patent No. 1,486,189, dated March 11, 1924, there is shown a device for supporting the heddle bars intermediate their ends which permits the bars to be easily and conveniently inserted in and removed from the

20 heddle frame.

My present invention contemplates certain improvements in the device shown and described in the Letters Patent above mentioned, whereby the supporting device may 25 be adjusted with respect to the top and bottom rails of the frame, so that the heddle supporting bars will be properly positioned and the heddles will not bind on the supporting bars, or on the other hand be permitted too great an up and down movement thereon.

The nature and characteristic features of my present invention will be more readily understood from the following description, taken in connection with the accompanying 35 drawings forming part hereof, in which:

Figure 1 is an elevational view of a heddle frame provided with heddle bar supporting devices embodying the main features of my present invention;

40 Fig. 2 is a fragmentary detail thereof, enlarged;

Fig. 3 is a sectional view taken approximately on the line 3—3 of Fig. 2, the parts being shown in the normal positions assumed

45 while supporting the heddle bar;

Fig. 4 is a similar view, but with the parts in the open position for the purpose of removing or mounting the heddle bar therein; and

50 Fig. 5 is a perspective view of a slidable locking member constituting one of the elements of the present invention.

Referring to the drawings, the heddle frame there shown comprises top and bottom rails 10, connected at their ends by means of 55 the side strips 11. Extending from end to end of the heddle frame and arranged near the top and bottom rails 10, in the usual manner, are the heddle supporting bars 12, on which the heddles 13 are mounted in the customary manner.

The devices comprising the novel portion of the present invention are mounted at suitable locations on the inner edges of the top and bottom rails 10.

65 On the inner side of the rail 10 there is provided a recess in which is seated a nut 14. The shank of a bolt 15 is threaded in the nut 14. The bolt 15 extends through the rail 10 beyond the outer edge thereof. Upon the 70 end of the bolt 15 there is mounted a wing nut 16, and if desired, a lock washer 17 of any preferred type may be interposed between the wing nut 16 and the outer edge of the rail 10.

The other end of the bolt 15, which projects toward the interior of the frame, is provided with a flattened portion 18, to which a plate member 19 is secured by rivets 20. The plate member 19 is provided with recesses 21, which are adapted to receive and support the 80 heddle supporting bars 12.

Slidably mounted with respect to the plate 85 19 is a lock member 30, which is provided with a central longitudinal slot 31. The rivets 20, for securing the plate 19 to the head portion 18 of the bolt 15, extend through the slot 31, and the enlarged head portion 22 of said rivets 20 serve to maintain the lock member 30 in proper slidable relationship with respect to the plate member 19. The lock 90 member 30 is also provided with lip portions 32, which are adapted, when the lock member 30 is in the operative position, to extend downward over the heddle bars 12 and thereby retain the same within the recesses 95 21 of the plate member 19.

One end of the lock member 30 is bent over as at 33, being provided with an aperture 34 in the bent over portion. The smooth portion of the shank of the bolt 15 passes through 100 the aperture 34 above mentioned.

Mounted on the bolt 15 is a coil spring 40, which is arranged between the bent over portion 33 of the lock member 30 and the nut 14

which is seated in the recess. If desired, a washer 41 may be interposed between the end of the spring 40 and the bent over portion 33 of the slide member 30, to afford a better bearing for the end of the spring 40.

The movement of the lock member 30 under tension of the spring 40, is limited by the longitudinal extent of the slot 31, the respective ends of the slot encountering the rivets 10 at each end of the movement.

The operation of the device may now be readily understood. The supporting device being mounted in the heddle frame at desired locations upon the top and bottom rails 15 thereof, and the heddle bars with the heddles mounted thereon being placed in the frame in the usual manner, with the ends thereof secured in position in the side strips 11 of the frame by fastening devices of any preferred 20 type, the lock member 30 is then manually pushed to the open position as shown in Fig. 4 of the drawings.

The heddle bars 12 are now inserted in the recesses 21 provided in the plate member 19, 25 and thereafter the lock member 30 is released and permitted to return, under tension of the spring 40, to the normal locking position as shown in Fig. 3 of the drawings, being thereafter held in that position by the coil 30 spring 40.

The lip portion 32 of the lock member 30 will now serve to maintain the heddle bars 12 within the recesses 21 of the plate member 19, and will securely hold the same against displacement during the operation of the loom.

When it is desired to remove the heddle supporting bars from the supporting devices, it will be necessary merely to again push and hold the lock member 30 in the position shown 40 in Fig. 4 of the drawings, and the heddle bars 12 may then be readily disengaged from the supporting devices.

Should it be found at any time that the heddle supporting bars are so located that an undue tension is placed upon the heddles, whereby the same will bind upon the heddle supporting bars, or on the other hand, should it be found that the heddle bars are so positioned that the heddles are permitted too 50 much up and down movement in the frame, the proper adjustment of the device for supporting the heddle bars may easily be made by first removing the heddle bars from the supporting device, then loosening the wing nut 55 16, then threading the bolt 15 in or out with respect to the nut 14 until the recesses 21 in the plate member 19 are brought to the proper location, after which the wing nut 16 may again be tightened on the bolt 15.

While the plate member 19 is shown as provided with two recesses 21, for use in a heddle frame of the duplex type, in which pairs of heddle supporting bars are arranged side by side, it will, of course, be understood 65 that the device may, if desired, be so arranged

as to support single bars at the top and bottom rails, respectively, of the frame, in which event the frame 19 will be provided with but a single recess and the slide member will be correspondingly shaped.

It will be seen that with devices constructed as hereinbefore described, the heddle bars will be efficiently supported intermediate their ends and undue lateral movement of the same will be effectively prevented. Adjustment of 75 the supporting devices with respect to the top and bottom rails may be quickly and conveniently made, so that the heddle bars may at all times be properly positioned.

Having thus described the nature and characteristic features of my invention, what I claim as new, and desire to secure by Letters Patent, is:

1. In a heddle frame, the means for supporting the heddle bars intermediate their ends, comprising a bolt member extending entirely through the heddle frame rail and adjustably mounted with respect thereto, a plate member carried at the inner end of the bolt member having recesses adapted to receive and support the heddle supporting bars, a lock member slidably mounted upon said plate member and having overhanging lip portions adapted to engage the heddle supporting bars and retain the same in the recesses in the plate member, and a spring mounted on the bolt member adapted to impel the lock member to the locking position.

2. In a heddle frame, the means for supporting the heddle bars intermediate their ends, comprising a bolt member extending entirely through the heddle frame rail, a nut mounted in the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the heddle supporting bars, a lock member slidably mounted upon said plate member and having overhanging lip portions adapted to engage the heddle supporting bars and retain the same in the recesses in the plate member, and a spring mounted on the bolt member adapted to impel the lock member to the locking position.

3. In a heddle frame, the means for supporting the heddle bars intermediate their ends, comprising a bolt member extending entirely through the heddle frame rail, a nut mounted in the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the

5 heddle supporting bars, a lock member slidably mounted upon said plate member and having overhanging lip portions adapted to engage the heddle supporting bars and retain the same in the recesses in the plate member, rivets passing through a slot in the lock member and serving to guide and limit the movement of the lock member, said rivets also serving to secure the plate member to the 10 bolt, and a spring mounted on the bolt member adapted to impel the lock member to the locking position.

4. In a heddle frame, the means for supporting the heddle bars intermediate their ends, comprising a bolt member extending entirely through the heddle frame rail, a nut mounted in the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the 20 heddle supporting bars, a lock member slidably mounted upon said plate member and having overhanging lip portions adapted to engage the heddle supporting bars and retain the same in the recesses in the plate member, said lock member having a bent over portion at one end, said bent over portion being provided with an aperture through which the bolt extends, and a spring mounted on the bolt member adapted to impel the lock member to the locking position.

5. In a heddle frame, the means for supporting the heddle bars intermediate their ends, comprising a bolt member extending entirely through the heddle frame rail, a nut mounted in the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the 30 heddle supporting bars, a lock member slidably mounted upon said plate member and having overhanging lip portions adapted to engage the heddle supporting bars and retain the same in the recesses in the plate member, rivets passing through a slot in the lock member and serving to guide and limit the movement of the lock member, said rivets also serving to secure the plate member to the bolt, said lock member having a bent over portion at one end, said bent over portion being provided with an aperture through which the bolt extends, and a spring mounted on the bolt member adapted to impel the lock member to the locking position.

6. In a heddle frame, the means for supporting the heddle bars intermediate their ends, comprising a bolt member extending entirely through the heddle frame rail, a nut seated in a recess in the inner edge of the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the 40 heddle supporting bars, a lock member slidably mounted upon said plate member and having overhanging lip portions adapted to engage the heddle supporting bars and retain the same in the plate member, rivets passing through a slot in the lock member and serving to guide and limit the movement of the lock member, said rivets also serving to secure the plate member to the bolt, said lock member having a bent over portion at one end, said bent over portion being provided with an aperture through which the bolt extends, and a spring mounted on the bolt member adapted to impel the lock member to the locking position.

7. In a heddle frame, the means for supporting the heddle bars intermediate their ends, comprising a bolt member extending entirely through the heddle frame rail, a nut seated in a recess in the inner edge of the heddle frame rail and in threaded engagement with said bolt member, a nut threaded on the outer end of said bolt member adapted when screwed down to secure said bolt in fixed relationship with respect to the rail, a plate member carried at the inner end of the bolt member having recesses adapted to receive and support the heddle supporting bars, a lock member slidably mounted upon said plate member and having overhanging lip portions adapted to engage the heddle supporting bars and retain the same in the plate member, rivets passing through a slot in the lock member and serving to guide and limit the movement of the lock member, said rivets also serving to secure the plate member to the bolt, said lock member having a bent over portion at one end, said bent over portion being provided with an aperture through which the bolt extends, and a spring mounted on the bolt member adapted to impel the lock member to the locking position.

In testimony whereof, I have hereunto signed my name.

JOHN JACOB KAUFMANN.
